UNITED STATES PATENT OFFICE.

WILLIAM J. PATCHELL, OF ST. LOUIS, MISSOURI.

SPACING-MACHINE.

1,036,695.

Specification of Letters Patent. Patented Aug. 27, 1912.

Application filed July 1, 1907, Serial No. 381,714. Renewed January 26, 1912. Serial No. 673,675.

To all whom it may concern:

Be it known that I, WILLIAM J. PATCHELL, a citizen of the United States, residing at St. Louis, in the State of Missouri, have invented certain new and useful Improvements in Spacing-Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 The present invention relates to a device for controlling the operation of punching machines, particularly machines designed for the purpose of punching rivet and bolt holes in structural iron or steel, whereby the 20 holes punched are caused to conform in arrangement to a certain predetermined pattern without the necessity of previously marking out this pattern on the work itself.

One object of my invention is to provide 25 a machine of the character above referred to in which may be used a paper or other pattern or templet upon which appears, upon a reduced scale, the design to which the 30 holes in the work are to conform, which pattern or templet may be a working drawing, in accordance with which the work is being prepared, or a blueprint thereof.

A further object of my invention is to produce a machine of the nature referred to 35 which shall be entirely automatic in its operation, requiring the attention of an operator only in starting and stopping the same for the purpose of supplying new material to be punched or for changing the 40 pattern.

To these ends my invention preferably comprises two carriages, one adapted to carry a perforated pattern or templet and the other constructed to feed the material to 45 be punched to suitable punching mechanism, which carriages are arranged to be moved at relative speeds proportional to the scale upon which the pattern is made, a device adapted to engage the pattern, and means 50 whereby, when said device encounters a perforation in the pattern, the feeding movement will be temporarily suspended and a hole punched in the work, after which the feeding movement will be automatically con-

tinued. In place, however, of a movable 55 pattern or templet and a stationary device coöperating therewith, I may, if desired, employ a stationary pattern and so construct the mechanism as to cause the coöperating device to be moved over the same, 60 such a construction being obviously within the scope of my invention.

In the accompanying drawings, in which I have illustrated one construction in which my invention may be embodied, I have not 65 shown in detail the punching mechanism, as any suitable or preferred form of such mechanism may be employed, but have illustrated only as much thereof as will be necessary to the complete understanding of the 70 controlling mechanism in which my invention consists.

In the drawings: Figure 1 is a side elevation of my improved machine; Fig. 2 is a plan view and Fig. 3 an elevation, 75 partly broken away, of the pattern carriage; Fig. 4 is a plan view of the machine; Fig. 5 is a transverse section taken substantially on the line 5—5 of Fig. 1, and looking in the direction indicated by the arrows 80 thereon; Fig. 6 is an enlarged plan view of a portion of the machine with the pattern and work feeding carriages removed or broken away; Figs. 7 and 8 are detail transverse sectional views of the magnet holding 85 blocks or castings; Fig. 9 is a detail transverse sectional view of the pattern carriage and associated devices; Fig. 10 is a plan view of the support for the contact pin; Fig. 11 is a plan view of the pattern or 90 templet; and Fig. 12 is a diagrammatic view illustrating the electrical circuits and connections, and Fig. 13 is a sectional view, to be described, of the punching mechanism and work carriage.

Similar reference characters indicate similar parts throughout the several views of the drawings.

Mounted upon a series of uprights, 12, 12, are bearing boxes 13, 13, in which are journaled a series of parallel shafts 14, 14, carrying rollers 15 and 16 for supporting the beam, plate, or other article to be punched. The uprights 12, 12, are preferably four in number, arranged with two at 105 either end of the machine as shown in Fig. 4, but it will be obvious that a different number might be employed if desired. The

bearing boxes 13 are preferably connected to the uprights 12 by means of adjusting screws 17, whereby the vertical position of the rollers 15 and 16 may be adjusted in accordance with the requirements of the work. The rollers 15 are preferably rigidly mounted on the shafts 14, while the rollers 16 are loosely mounted for movement longitudinally thereof to accommodate work of different widths, and are provided with annular grooves 18 for the reception of the flanges of I-beams and channels, as shown in Fig. 5.

In front of the uprights 12 are a plurality of horizontal parallel tracks 19, upon which run rollers 20, supporting a carriage 21, carrying the operating mechanism of the machine. One set of rollers 20 is mounted upon a horizontal shaft 22, journaled in the carriage 21, and provided with one or more pinions 23, engaging a corresponding rack or racks 24, arranged parallel to the tracks 19. The shaft 22 also carries a bevel pinion 25, co-operating with a corresponding pinion 26, carried by a vertical shaft 27, journaled in the carriage 21 and provided with a suitable hand wheel 28. It will be seen that rotation of the hand wheel 28 will result in movement of the carriage 21 toward or from the uprights 12. By this means the machine may be adjusted to accommodate work of different widths.

As above noted the carriage 21 carries the principal operating mechanism of the controlling device, together with the source of power therefor, the latter comprising an electric motor 29, adapted to be coupled to a driving shaft 30, by an electrically operated clutch 31, of any well known or preferred construction. Upon the shaft 30 is mounted a pinion 32, and this shaft is also preferably provided with a suitable electrically operated brake 33, which may be of any well known type, such a brake being indicated in Fig. 12 but being omitted from Figs. 1 and 6.

Mounted to slide upon suitable ways 34, arranged on the carriage 21, is a pattern holder or supporting carriage 35, adapted to carry a suitable pattern or templet 36, held in position thereon by spring clamps 37, or other equivalent devices. The pattern carriage 35 also carries, beneath the pattern 36, an insulated contact plate 38, preferably of copper, and provided with a suitable binding post (not shown) for the attachment of a battery wire.

Upon a standard 39, adjustably carried by one of the ways 34, is pivotally mounted an arm or lever 40, on which is slidably mounted a block 41, held in adjusted position on said arm by a suitable set screw 42. Downward movement of the arm 40 toward the pattern 36 may, if desired, be limited by a suitable stop 43, adjustably

carried by the opposite way 34. Adjustably held in position in the block 42, as by a suitable clamping device 44, is a contact pin 45, provided with a suitable binding post 46, adapted to receive a wire from a battery 48 (see Fig. 12) or other source of electrical current, the other wire from which is connected with the contact plate 38.

The pattern or templet employed in my improved machine is preferably of paper, is made to represent the beam or other number to be punched upon a preferably reduced scale, and is provided with perforations 47 at the points corresponding with those at which said member is to be punched. This pattern may, if desired, be a working drawing or a blueprint thereof, which has been provided with perforations at the proper points.

It will now be seen that as the pattern carriage 35 is moved along its ways 34, by mechanism hereinafter described, the contact pin 45 will ride over the surface of the pattern or templet 36, and that when a perforation 47 is encountered said pin will drop through the same, thus closing the circuit from the battery 48 through the contact plate 38. The closing of this circuit results in setting into operation certain mechanism hereinafter described.

The means whereby the pattern or templet and the beam or other member to be punched are given their corresponding feeding movements will now be described.

The pattern carriage 35 is provided on its under side with a rack 49 engaged by a pinion 50, suitably journaled in the frame of the carriage 21, said pinion 50 engaging a gear 51, mounted on a shaft 52, also journaled in the frame of the carriage 21. The shaft 52 carries at one end a hand wheel 53, whereby the parts may be moved and adjusted by hand if desired, and at its other end a pinion 54, engaging a rack 55, on a feed carriage 56, preferably mounted on rollers 57 (see Fig. 5), suitably journaled in the frame of the carriage 21. The pinions 50 and 54 and gear 51 are designed in accordance with the scale employed for the pattern or templet so that the relative movements of the carriages 35 and 56 will be proportional to said scale. For example if the scale adopted to be one inch to one foot, this gearing will be so designed as to produce in the carriage 56 a movement of one foot for every inch through which the carriage 35 is moved. The shaft 52 carries a gear 58, connected through suitable reducing gears 59, 60, and 61 and bevel gear 62, with the bevel gear 32 on the power shaft 30.

Mounted in suitable castings 63, secured to the upper side of the feed carriage 56, is a series of strong electro-magnets 64 and 65, adapted to attract the beam or other mem-

ber placed upon the rollers 15 and 16 and to cause the same to move in unison with the feed carriage 56. The magnets 64 are arranged horizontally to coöperate with an I-beam, channel, or other member provided with a flange, as shown in full lines in Fig. 5, while the magnets 65 are arranged vertically to coöperate with a plate, as indicated by dotted lines in said figure. The magnets 64 and 65 preferably alternate with one another, as indicated in Figs. 4 and 6.

The electrical circuits, connections, and appliances, whereby the operation of the punching mechanism is controlled by the devices above described, are illustrated in diagrammatic form in Fig. 12, and will now be described. These appliances include, in addition to those heretofore referred to, a manually operated main switch 66 for controlling the admission of current from any suitable source of supply to the machine as a whole, a manually operated reversing switch 67 for controlling the direction of rotation of the motor 29, a manually operated magnet switch 68 for controlling the electromagnets 64 and 65, a pair of bus bars 69 and 70 from which the current is distributed to the various circuits hereinafter referred to, a manually operated speed controller 71 for the motor 29, a switch 72 adapted to be controlled by the punch carrying head 73 as hereinafter described, an electrically controlled clutch 74 for starting and stopping the punching mechanism, and five electrically controlled switches 75, 76, 77, 78 and 79, together with certain circuits, hereinafter described, for operatively connecting these various appliances.

The switches 66, 67, and 68 together with the bus bars 69 and 70 may be of any suitable well known or preferred construction, and are preferably arranged upon a switch board located at a convenient distance from the machine.

The electromagnetic switch 75 is preferably constructed as shown and comprises a frame 80, containing an electromagnet 81, provided with an armature 82, carrying an insulated contact bar 83, coöperating with suitable contact points 84 and 85. The switches 75, 76, 77, 78 and 79 may all be of substantially the same construction, the switches 75 and 76, however, being arranged to open the circuits governed by them when their magnets are energized, while the switches 77, 78 and 79 are arranged to close their corresponding circuits when energized.

The electrically controlled clutch 74 for starting and stopping the punching mechanism may be of any suitable construction, but as herein shown comprises a frame 86, containing an electromagnet 87, provided with an armature 88, operatively connected with a bell crank lever 89, adapted to operate the clutch 90.

The switch 72 comprises a curved plate 91, having a contact portion 92 and an insulated or circuit breaking portion 93, an arm 94, adapted to close the circuit through the portion 92 of the plate 91 and arranged in the path of a pin or trip 95 on the punch carrying head 73, and a spring 96 adapted normally to hold the arm 94 in the position shown in Fig. 12.

The circuits connecting the above described appliances have been generically designated by the numerals 97, 98, 99, 100, and 101, respectively. The circuit 97 starts from the battery 48, thence passes to the contact plate 38, thence to the contact pin 45, thence through the switch 72, thence through the magnets of the switches 78 and 79, and back to the battery. The circuit 98 leaves the bus bar 69, thence passes to the collector 71, thence to the motor 29, thence through the contacts of the switch 75, thence through the magnet of the switch 76, thence to the bus bar 70. The circuit 99 leaves the bus bar 69, thence passes through the magnet of the switch 75, thence through the contacts of the switches 78 and 79, thence to the bus bar 70. The circuit 100 leaves the bus bar 69, thence passes to the brake 33, thence through the contacts of the switch 76, thence through the magnet of the switch 77, thence to the bus bar 70. The circuit 101 leaves the bus bar 69, thence passes through the magnet 86 of clutch 74, thence through the contacts of the switch 77, thence to the bus bar 70.

In addition to the above circuits a circuit 102 derives current from circuit 98 by connection therewith at 103, which current passes through the clutch 31, thence to the bus bar 70.

The operation of the above described mechanism is as follows: Assuming the carriages 35 and 56 to be at substantially their limit of movement in one direction, the switch 67 turned so as to cause the motor, when started, to move these carriages forward in the opposite direction, a beam or other member to be punched placed upon the rolls 15 and 16, and a pattern or templet in position on the carriage 35. The operator now allows the arm 40 to drop, causing the contact pin 45 to rest upon the surface of the pattern, and throws in the switches 66 and 68. Current is at once supplied to the bus bars 69 and 70 and passes through the switch 68 to the magnets 64 and 65, thus securely clamping the work to the carriage 56. The circuits 98 and 102 are at this time closed, the parts being in substantially the position shown in Fig. 12, and current passes from the bus bar 69 through the controller 71 to the motor. At the same time current flowing in circuit 102 throws in the clutch 31, thus starting the machine. From the motor the current in circuit 98, passing the switch 120

1. 75, passes to the magnet of the switch 76, thus opening circuit 100 and releasing the brake 33, and returns to the bus bar 70. The machine being thus started the carriages 35 and 56 are fed forward until the contact pin 45 encounters a perforation in the pattern, when it immediately drops therethrough and closes the battery circuit 97 through the contact plate 38. Current at 10 once passes to the magnets of the switches 78 and 79, causing these switches immediately to close circuit 99, over which current now passes from the bus bar 69 to the magnet of the switch 75, thus opening circuits 98 and 15 102, shutting off the current to the motor 29, releasing the clutch 31, and allowing the motor to "coast". The opening of circuit 98 causes the magnet in switch 76 to release its armature, thus closing circuit 100, applying 20 the brake 33, and energizing the magnet in switch 77. Switch 77 at once closes circuit 101, causing the magnet 87 to throw in the clutch 90 and start the punching mechanism. As the punch head 73 moves downwardly the pin or trip 95 wipes past the arm 94, which remains in contact with the portion 92 of the plate 91, and springs back to its normal position after the pin 95 has passed it, these parts now being in the position shown in Fig. 12. Upon the upward movement of the punch head, and after it has cleared the work, the pin 95 pulls the arm 94 upwardly and out of contact with the portion 92 of the plate 91, thus opening 30 circuit 97 long enough to allow the magnets in the switches 78 and 79 to release their armatures, thus opening circuit 99. This causes switch 75 to close circuit 98, throwing in the clutch 31, starting the motor 29, and 35 causing switch 76 to open circuit 100. This in turn releases the brake 33 and permits switch 77 to open circuit 101, thus releasing the clutch 90 and stopping the punching mechanism. By this time the pin 95 in its 40 upward movement has cleared the arm 94, which has sprung back to its normal position in contact with the portion 92 of the plate 91, thus tending to close circuit 97. In the meantime, however, the pattern carriage 35 45 has moved slightly forward, carrying the opening in the pattern away from the contact pin 45 and thus opening the circuit 97 at this point. It will be observed however that the parts are left in such position as to 50 cause circuit 97 to be immediately closed as soon as the contact pin 45 encounters another hole in the pattern. The above operation is repeated whenever a hole in the pattern is encountered, until the desired number 55 of holes has been punched. The operator now raises the arm 40, reverses the switch 67, and allows the carriages to be run back to their original positions, after which the main switch 66 is opened to stop the machine and release the work.

While I, in order that my invention may be more readily understood, have chosen to illustrate and describe the same as embodied in a particular construction, I wish it to be distinctly understood that I do not limit myself to the precise construction shown, it being obvious that many changes might be made therein without departing from the spirit and scope of my invention. It will also be obvious that instead of the punching mechanism herein shown and described, suitable cutting, marking, or other mechanism might be employed, and that my invention would be equally useful with such mechanism.

80 Preferably, and as shown in Fig. 13, the punching or other mechanism, indicated generically in the said figure by the numeral, 122, will be provided with a graduated scale 120 adapted to coöperate with a pointer or indicator 121 carried by the carriage 21. The graduations on the scale 120 are of such a character as will indicate the relative position of the punching mechanism and the carriage 21, as the latter is moved along the tracks 19, as heretofore described. With this construction the parts may be readily adjusted to bring the line of holes punched at any desired distance from the edge of the work.

90 Having described my invention and set forth its merits, what I claim is:—

1. In a machine of the character described, the combination with means for supporting a pattern or templet, and means for feeding the work, of means for causing said pattern supporting means and said work feeding means to move at different speeds, and means operating automatically to temporarily stop at predetermined 100 periods the movement of the pattern supporting means and work feeding means, substantially as described.

2. In a machine of the character described, the combination with an apertured pattern or templet and means for feeding the same, of means coöperating with and controlled by said pattern or templet for stopping said feeding means, substantially 110 as described.

3. In a machine of the character described, the combination with a pattern or templet and means for feeding the same, of electrically actuated means coöperating with and controlled by said pattern or templet for stopping said feeding means, substantially 120 as described.

4. In a machine of the character described, the combination with an apertured pattern or templet, of work feeding means, and means coöperating with and controlled by said pattern or templet for stopping said work feeding means, substantially as described.

5. In a machine of the character de-

- scribed, the combination with a pattern or templet, of work feeding means, and electrically actuated means coöperating with and controlled by said pattern or templet 5 for stopping said work feeding means, substantially as described.
6. In a machine of the character described, the combination with work feeding means and means for supporting and feeding an apertured pattern or templet, of means coöperating with and controlled by said pattern or templet for stopping said work feeding means, substantially as described.
- 10 7. In a machine of the character described, the combination with work feeding means and means for supporting and feeding a pattern or templet, said work feeding and pattern feeding means being constructed and arranged to cause said work and said pattern to move at different speeds, of means coöperating with and controlled by said pattern or templet for stopping said work feeding means, substantially as described.
- 15 8. In a machine of the character described, the combination with work feeding means and means for supporting and feeding a pattern or templet, of electrically actuated means coöperating with and controlled by said pattern or templet for stopping said work feeding means, substantially as described.
- 20 9. In a machine of the character described, the combination with work feeding means and means for supporting and feeding an apertured pattern or templet, of means coöperating with and controlled by said pattern or templet for stopping said work feeding means and said pattern feeding means, substantially as described.
- 25 10. In a machine of the character described, the combination with work feeding means, work feeding means, and means for supporting and feeding an apertured pattern or templet, of means coöperating with and controlled by said pattern or templet for stopping said work feeding means and for causing said punching means to be actuated, substantially as described.
- 30 11. In a machine of the character described, the combination with punching means, work feeding means, and means for supporting and feeding a pattern or templet, of means coöperating with and controlled by said pattern or templet for stopping said work feeding means and for causing said punching means to be actuated, substantially as described.
- 35 12. In a machine of the character described, the combination with punching means, work feeding means, and means for supporting and feeding a pattern or templet, of means coöperating with and controlled by said pattern or templet for stopping said work feeding means and for causing said punching means to be actuated, substantially as described.
- 40 13. In a machine of the character described, the combination with punching means, work feeding means, and means for supporting and feeding a pattern or templet, of means coöperating with and controlled by said pattern or templet for stopping said work feeding means and said pattern feeding means, and for causing said punching means to be actuated, substantially as described.
- 45 14. In a machine of the character described, the combination with punching means, work feeding means, and means for supporting and feeding a pattern or templet, of means coöperating with and controlled by said pattern or templet for stopping said work feeding means and for causing said punching means to be actuated, and means controlled by said punching means for again starting said work feeding means, substantially as described.
- 50 15. In a machine of the character described, the combination with punching means, work feeding means, and means for supporting and feeding a pattern or templet, of electrically controlled means coöperating with and controlled by said pattern or templet for stopping said work feeding means and for causing said punching means to be actuated, and means controlled by said punching means for again starting said work feeding means, substantially as described.
- 55 16. In a machine of the character described, the combination with punching means, work feeding means, and means for supporting and feeding a pattern or templet, of means coöperating with and controlled by said pattern or templet for stopping said work feeding means and said pattern feeding means and for causing said punching means to be actuated, and means controlled by said punching means for again starting said work feeding means and said pattern feeding means, substantially as described.
- 60 17. In a machine of the character described, the combination with an apertured pattern or templet, a device coöperating therewith, and means for causing a relative movement of said pattern and said coöperating device, of means controlled by said coöperating device for stopping said relative movement at times determined by said pattern or templet, substantially as described.
- 65 18. In a machine of the character described, the combination with a pattern or templet, a device coöperating therewith, and

means for causing a relative movement of said pattern and said coöperating device, of electrically actuated means controlled by said coöperating device for stopping said 5 relative movement at times determined by said pattern or templet, substantially as described.

19. In a machine of the character described, the combination with work feeding 10 means, of an apertured pattern or templet, a device coöperating therewith, means for causing a relative movement of said pattern and said coöperating device, and means controlled by said coöperating device for stopping 15 said work feeding means at times determined by said pattern or templet, substantially as described.

20. In a machine of the character described, the combination with work feeding 20 means, of a pattern or templet, a device coöperating therewith, means for causing a relative movement of said pattern and said coöperating device, and electrically actuated means controlled by said coöperating 25 device for stopping said work feeding means at times determined by said pattern or templet, substantially as described.

21. In a machine of the character described, the combination with a work support, 30 punching means, and means for causing a relative movement of said punching means and the work on said support, of an apertured pattern or templet, a device coöperating therewith, means for causing a 35 relative movement of said pattern or templet and said coöperating device, and means controlled by said coöperating device for stopping the relative movement of said punching means and said work, substantially 40 as described.

22. In a machine of the character described, the combination with a work support, punching means, and means for causing a relative movement of said punching 45 means and the work on said support, of a pattern or templet, a device coöperating therewith, means for causing a relative movement of said pattern or templet and said coöperating device, the relative movement 50 of the punching means and the work being different from that of the pattern or templet and its coöperating device, substantially as described.

23. In a machine of the character described, the combination with a work support, punching means, and means for causing a relative movement of said punching 55 means and the work on said support, of a pattern or templet, a device coöperating therewith, means for causing a relative movement of said pattern or templet and said coöperating device, and electrically actuated means controlled by said coöperating device for stopping the relative

movement of said punching means and said 65 work, substantially as described.

24. In a machine of the character described, the combination with a work support, punching means, and means for causing a relative movement of said punching 70 means and the work on said support, of a pattern or templet, a device coöperating therewith, means for causing a relative movement of said pattern or templet and said coöperating device, and means controlled by said coöperating device for stopping the relative movement of said punching means and said work and for causing 75 said punching means to be actuated, substantially as described.

25. In a machine of the character described, the combination with a work support, punching means, and means for causing a relative movement of said punching means and the work on said support, of a 80 pattern or templet, a device coöperating therewith, means for causing a relative movement of said pattern or templet and said coöperating device, means controlled by said coöperating device for stopping the 85 relative movement of said punching means and said work and for causing said punching means to be actuated, and means controlled by said punching means for again 90 starting said relative movement, substantially as described.

26. In a machine of the character described, a work support including an upright, bearings carried by said upright, a shaft journaled in said bearings, a pair of 100 work supporting rollers mounted on said shaft, and traveling means located at one side of said rollers for engaging said work and moving it on said rollers, substantially 105 as described.

27. In a machine of the character described, a work support including an upright, vertically adjustable bearings carried by said upright, a shaft journaled in said 110 bearings, and a pair of work supporting rollers mounted on said shaft, substantially as described.

28. In a machine of the character described, a work support including an upright, bearings carried by said upright, a shaft journaled in said bearings, a pair of work supporting rollers mounted on said shaft, one of said rollers being loosely 115 mounted on said shaft for movement longitudinally thereof, and traveling means located at one side of said rollers for engaging the work and moving it on said rollers, substantially as described.

29. In a machine of the character described, a work support including an upright, bearings carried by said upright, a shaft journaled in said bearings, and a pair 120 of work supporting rollers mounted on said

shaft, one of said rollers being provided with an annular groove, substantially as described.

30. In a machine of the character described, the combination with a work support, and means traveling parallel with the support for feeding the work over said work support, of means for adjusting said feeding means toward and from said work support at right angles thereto, substantially as described.

31. In a machine of the character described, the combination with a work support, of a track, a carriage movable on said track toward and from said work support, means for moving said carriage on said track, and means on said carriage and traveling parallel with the work support for feeding the work over said work support, substantially as described.

32. In a machine of the character described, the combination with a work support, of a track, a carriage movable on said track toward and from said work support, means for moving said carriage on said track, means on said carriage for feeding the work over said work support, and a motor, also on said carriage, for actuating said feeding means, substantially as described.

33. In a machine of the character described, the combination with means for feeding a pattern or templet, of a motor for actuating said feeding means, and means controlled by said pattern or templet for stopping said motor, substantially as described.

34. In a machine of the character described, the combination with means for feeding a pattern or templet, of a motor for actuating said feeding means, and electrically actuated means controlled by said pattern or templet for stopping said motor, substantially as described.

35. In a machine of the character described, the combination with means for feeding a pattern or templet, of a motor for actuating said feeding means, a brake for stopping said feeding means, and means controlled by said pattern or templet for stopping said motor and for applying said brake, substantially as described.

36. In a machine of the character described, the combination with means for feeding a pattern or templet and means for feeding the work, of a motor for actuating said feeding means, and means controlled by said pattern or templet for stopping said motor, substantially as described.

37. In a machine of the character described, the combination with means for feeding a pattern or templet, of a motor, a clutch connecting said motor and feeding means, and means controlled by said pattern or templet for releasing said clutch, substantially as described.

38. In a machine of the character described, the combination with means for feeding a pattern or templet, of a motor, a clutch connecting said motor and feeding means, and electrically actuated means controlled by said pattern or templet for releasing said clutch, substantially as described.

39. In a machine of the character described, the combination with means for feeding a pattern or templet, of a motor, a clutch connecting said motor and feeding means, a brake for stopping said feeding means, and means controlled by said pattern or templet for releasing said clutch and for applying said brake, substantially as described.

40. In a machine of the character described, the combination with means for feeding a pattern or templet and means for feeding the work, of a motor, a clutch connecting said motor and feeding means, and means controlled by said pattern or templet for releasing said clutch, substantially as described.

41. In a machine of the character described, the combination with punching means and means for feeding work to said punching means, of a motor for actuating said feeding means, and pattern controlled means for stopping said motor, substantially as described.

42. In a machine of the character described, the combination with punching means and means for feeding work to said punching means, of a motor for actuating said feeding means, and electrically actuated pattern controlled means for stopping said motor, substantially as described.

43. In a machine of the character described, the combination with punching means and means for feeding work to said punching means, of a motor for actuating said feeding means, a brake for stopping said feeding means, and pattern controlled means for stopping said motor and for applying said brake, substantially as described.

44. In a machine of the character described, the combination with punching means and means for feeding work to said punching means, of a motor, a clutch for connecting said motor and feeding means, and pattern controlled means for releasing said clutch, substantially as described.

45. In a machine of the character described, the combination with punching means and means for feeding work to said punching means, of a motor, a clutch for connecting said motor and feeding means, and electrically actuated pattern controlled means for releasing said clutch, substantially as described.

46. In a machine of the character described, the combination with punching means and means for feeding work to said punching means, of a motor, a clutch for

connecting said motor and feeding means, a brake for stopping said feeding means, and pattern controlled means for releasing said clutch and for applying said brake, substantially as described.

47. In a machine of the character described, the combination with a traveling pattern holder adapted to hold a perforated pattern and provided with a contact plate beneath said pattern, and means for securing a replaceable pattern on said holder, of a contact pin arranged above said pattern and adapted to make connection with said plate through the perforations in said pattern, substantially as described.

48. In a machine of the character described, the combination with a traveling pattern holder adapted to hold a perforated pattern and provided with a contact plate beneath said pattern, and means for securing a replaceable pattern on said holder, of a contact pin arranged above said pattern and adapted to make connection with said plate through the perforations in said pattern, and means for moving said pattern holder past said pin, substantially as described.

49. In a machine of the character described, the combination with a pattern carriage provided with an electrical contact plate, means for securing a replaceable pattern on said plate, and means for moving said carriage, of a pivoted arm, and a contact pin carried by said arm and co-operating with said plate, substantially as described.

50. In a machine of the character described, the combination of a pattern carriage, a contact plate supported on said carriage and insulated therefrom, means for securing a replaceable pattern on said contact plate, a contact pin arranged in relation to the contact plate and a pattern supported on it to control an electric circuit, and means for moving the pattern holder past said pin, substantially as described.

51. In a machine of the character described, the combination with a work support, and a carriage movable toward and from said support, of a pattern holder supported on said carriage and adapted to travel thereon, an electrical contact plate on said pattern holder, means for securing a replaceable pattern on the pattern holder, and a contact pin arranged in relation to said pattern and contact plate to make connection with the plate to control an electric circuit, substantially as described.

52. In a machine of the character described, the combination with work feeding means, of an electric circuit, pattern controlled means for closing said circuit, and means in said circuit for stopping said work feeding means when said circuit is closed, substantially as described.

53. In a machine of the character described, the combination with punching mechanism and means for feeding the work to said punching mechanism, of an electric circuit, means in said circuit for stopping said work feeding means when said circuit is closed, pattern controlled means for closing said circuit, and means operated by said punching mechanism for opening said circuit, substantially as described.

54. In a machine of the character described, the combination with work feeding means and an electric motor for actuating said feeding means, of an electric circuit, pattern controlled means for closing said circuit, an electrically operated switch controlled by said circuit, and a second circuit controlled by said switch and including said motor, substantially as described.

55. In a machine of the character described, the combination with a pattern or templet and means for feeding the same, of an electric circuit, means in said circuit for stopping said feeding means when said circuit is closed, and means controlled by said pattern for closing said circuit, substantially as described.

56. In a machine of the character described, the combination with work feeding means, an electric motor, and a clutch for connecting said feeding means and said motor, of an electric circuit, automatic means for closing said circuit, an electrically operated switch controlled by said circuit, and a second circuit controlled by said switch and including said motor and clutch, whereby when said first named circuit is closed said motor is stopped and said clutch released, substantially as described.

57. In a machine of the character described, the combination with punching mechanism and controlling mechanism therefor, of means controlled by said controlling mechanism for stopping said controlling mechanism and for starting said punching mechanism, and means controlled by said punching mechanism for starting said controlling mechanism and for stopping said punching mechanism, substantially as described.

58. In a machine of the character described, the combination with a pattern or templet, punching mechanism, and a clutch for stopping and starting said punching mechanism, of means controlled by said pattern or templet for throwing in said clutch, and means controlled by said punching mechanism for causing said clutch to be released, substantially as described.

59. In a machine of the character described, the combination with an electrically controlled work feeding carriage, of a magnet for holding the work on said carriage, substantially as described.

60. In a machine of the character de-

scribed, the combination with a work support, of means for feeding the work over said work support, and an electro-magnet for causing said work to move in unison 5 with said feeding means, substantially as described.

61. In a machine of the character described, the combination with a work support, of a work feeding carriage adjacent 10 said work support, and a magnet on said carriage, substantially as described.

62. In a machine of the character described, the combination with a work support, of a work feeding carriage adjacent 15 said work support, and a plurality of magnets on said carriage, some of said magnets being arranged horizontally and some vertically, substantially as described.

63. In machines of the character specified, 20 the combination of templet and work supports, mechanism arranged to move the templet and work in unison on the supports, the templet moving slower than the work, an index pin coöperating with the templet, 25 a tool acting on the work, and tool actuating mechanism controlled by the index pin.

64. In machines of the character specified, 30 the combination of templet and work supports, mechanism arranged to move the templet and work in unison on said supports, an index pin coöperating with the templet, a tool acting on the work, an electric circuit

controlled by the index pin, and tool actuating mechanism controlled by said circuit.

65. In machines of the character specified, 35 the combination of templet and work moving mechanism operating in unison; an index pin coöperating with the templet, a tool acting on the work, and means controlled by the index pin for stopping the templet and 40 work moving mechanisms.

66. In machines of the character specified, 45 the combination of templet and work moving mechanisms operating in unison, an index pin coöperating with the templet, a tool acting on the work, an electric circuit controlled by the index pin, and means controlled by said circuit for stopping the templet and work moving mechanisms.

67. In machines of the character specified, 50 the combination of templet and work moving mechanisms operating in unison, an index pin coöperating with the templet, a tool acting on the work, tool actuating mechanism controlled by the index pin, and means 55 also controlled by the index pin for stopping the templet and work moving mechanisms.

In testimony whereof I affix my signature in presence of two witnesses.

WILLIAM J. PATCHELL.
